MANUFACTURING COMPANY, OF PHILADELPHIA, PENNSYLVANIA, A CORPORATION
OF PENNSYLVANIA

CONDENSER FOR MIXED VAPORS

Application filed July 6, 1925. Serial No. 41,732.

My invention relates to the condensation into liquids of a mixture of vapors of different characteristics, and particularly of different temperatures of liquefaction at a given pressure.

In accordance with my invention, the condensation of such a vapor mixture is effected within a single condenser unit or shell, whereby there is effected economy in space, weight and cost as compared with systems utilizing separate condensers in which are condensed, respectively, the different vapors. By utilization of a single unit or shell, particularly when the condensation is to be effected under pressure other than atmospheric, as at sub-atmospheric pressure or under vacuum, the air leakage into the system is lessened, and in consequence there is a saving in power consumed by the ejectors or other air pumps utilized in maintaining the vacuum.

Further in accordance with my invention by recourse to a single condenser unit or shell, the pressure drop between the vapor inlet to the condensing apparatus and the connection to the air or vacuum pump or ejector is decreased, since the length of path between the vapor inlet and the air pump suction is shorter than in the case a plurality of condensers is utilized, one for each of the different vapors to be condensed, and all arranged in series and connected with each other.

Further in accordance with my invention, less piping and pipe connections are necessary for the cooling water system.

My invention resides in a system and apparatus of the character hereinafter described and claimed.

For an illustration of some of the various forms my apparatus may take, reference is to be had to the accompanying drawings, in which:

Fig. 1 is a vertical sectional view, partly in elevation, of condenser structure embodying my invention.

Fig. 2 is a top plan view of structure shown in Fig. 1.

Fig. 3 is a horizontal sectional view, taken on the line 3—3 of Fig. 1.

Fig. 4 is a horizontal sectional view taken on the line 4—4 of Fig. 1.

Fig. 5 is a fragmentary horizontal sectional view, partly in plan.

Fig. 6 is a vertical sectional view of a modified form of apparatus.

Fig. 7 is a vertical sectional view of a further modification.

By way of example, and for purposes of illustration of my invention, the condensation of a mixture of vapors of water and oil will be described.

In mixture with water vapor or steam, which is to be condensed under vacuum corresponding, for example, with an absolute pressure of two inches of mercury, at a temperature of about 101 degrees F., may be the vapors of oil condensing, under the same vacuum, at about 240 degrees F.

Referring to Figs. 1 to 5 inclusive, C is the shell of a single condenser unit, having the supports s, resting upon columns u, or equivalent. The shell C contains several banks of tubes t, through which is circulated the cooling medium, as water. These tubes terminate in tube sheets a and b at the top and bottom of the condenser, communicating at their upper ends with chambers in the cooling water box A and at their lower ends with compartments in the cooling water box B.

In the box A is a compartment c, to which is delivered the entering cooling water through the pipe D, which flows downwardly through the first group of tubes t into the chamber d in the lower water box B, through which it passes upwardly through the second group of tubes into the middle compartment e of the upper water box A, thence downwardly through the third group of tubes into the compartment f of the lower water box B, and thence upwardly through the fourth group of tubes into the compartment g in the upper box A, from which the cooling water is discharged through the pipe or outlet E.

In the box A the compartments c, e and g are formed and divided from each other by the walls or partitions h and i; and in the lower box B the compartments d and f are divided from each other by the wall j. Divid-

ing the interior of the shell C vertically is the plate or baffle F, preferably disposed between the second and third groups of tubes *t*. At suitable height the plate F is provided 5 with the opening or passage *k*, and at its lower end is spaced from the tube sheet *b* to form a second opening or passage *m*. Secured to the plate F, above the passage *k*, is a vapor-directing baffle *o*, and above it and 10 spaced laterally therefrom may be provided a second baffle plate *p* adjacent the air or suction port P, connected to ejectors, air pump or equivalent means for maintaining within the condenser a suitable sub-atmospheric 15 pressure or vacuum, as, for example, of the order of two inches mercury absolute, i. e., a so-called vacuum of 28 inches.

The condensate discharge port K is disposed adjacent the bottom of the shell C, and 20 communicates with the space formed by the baffle plate or member G making a tight joint with the inner wall of the shell C. The upper edge of the baffle G is disposed somewhat below the lower edge of the passage or port 25 *k* in the baffle F; this difference in levels is made of such magnitude as to effect substantially that friction head necessary to move the condensate through the chamber at the left of the plate F through the passage *m* and into 30 the chamber at the right of the baffle F.

The vapor mixture enters the shell C at the vapor inlet V, and passes around and between the tubes *t* of the third and fourth groups, causing the condensation of the oil vapors, 35 the oil condensate collecting in the lower part of the shell C to the left of the baffle F, Figs. 1 and 4, flowing through the passage *m* and rising in the compartment to the right of the baffle F to a height corresponding to the upper edge of the baffle structure G, overflowing 40 it into the space between the baffle G and the shell C and finding its way to the condensate outlet K.

The oil vapors condense at a higher temperature than the steam, and consequently, 45 the water vapors do not condense when they come into contact with the tubes *t* of the third and fourth groups, but pass through the opening *k* into the region above the oil condensate to the right of the baffle F, Fig. 1, and come into contact with the cooler tubes *t* of the second and first groups, some of the vapors passing upwardly around the baffle *o* toward the air suction or pump connection P. 50 Some of the steam condensate falls directly into the baffle chamber G, and that falling upon the oil condensate passes downwardly 55 therethrough and collects upon the tube sheet *b* outside of the baffle G. This water, however, is drawn off through the pipe *q*, Figs. 2 and 5, controlled by the valve *r*, and delivered through the pipe *v* into the condensate 60

outlet K, through which both the oil and water are drawn off and later readily separated.

The liquid oil is cooled, after condensation of the oil vapors, by the lower portions of the tubes of the fourth and third groups, and also by the lower portions of the tubes of the second and first groups to a temperature, particularly in the compartment to the right of the baffle F, Fig. 1, at least as low as, or preferably ten or more degrees lower than, the temperature at which the steam will condense under the vacuum conditions imposed. For example, the steam may condense at about 100 degrees F., and the oil condensate is cooled to such temperature or to suitably lower temperature, particularly when in the compartment to the right of the baffle F. The upper portions of the tubes *t* of the first and second groups with which the steam comes into contact are at suitably low temperature 85 for effecting substantially complete condensation, and the air passes around the baffle *p* to the air pump connection P and is removed to maintain the desired degree of vacuum, and in this passage the air is also suitably chilled or cooled to render it more readily compressible to atmospheric or other higher pressure.

By a construction of the character above described, the single condenser unit, in a single shell, occupies less space and is of less weight than in the case two separate condensers are utilized, one for condensing the one vapor, as oil, and the other for condensing the other vapor, as water. Furthermore, by the compact structure described, the air leakage is lessened, with consequent need for 95 lower duty air pumps or ejectors or the like.

Furthermore, the drop in pressure between the vapor inlet V and the air pump connection P is lessened, since the path between these points is shorter than in the case two separate condensers were utilized, connected in series with each other, with the vapor inlet to one of them, and the air pump connection to the other. In other words, the path is materially shortened, and in consequence the pressure drop along such path is decreased.

Furthermore, by an arrangement of the character described, less piping for the cooling water system is necessary, since the cooling water supply is simply connected to the pipe D and the pipe E is connected to the discharge line.

In Fig. 6 there is shown a generally similar arrangement, except that only two groups of cooling water tubes *t* are utilized, the upper cooling water box A being divided into two compartments only, and the lower box B forming a single compartment.

In Fig. 7 is shown a vertical sectional view of a horizontal type of condenser for the purposes herein described, and again comprising a single shell in which the different vapors of a mixture are successively condensed. In 130

this case the cooling water tubes extend horizontally, while as before the baffle F is disposed vertically. And in this case a second baffle structure G may be omitted.

5 While it is preferred that the cooling water be passed through the condenser tubes *t*, it will be understood by those skilled in the art that the arrangement is reversible, in that the vapors may be passed through the condenser 10 tubes and the cooling medium suitably directed for the purposes described around and between the tubes.

In apparatus of the character and for the purposes herein described, it may be desirable 15 to change the level of the oil or other condensate occupying the bottom of the unit, to vary the ratio of that portion of the cooling surface contacting with vapor or vapors to that contacting only with the oil or other 20 condensate. Such occasion sometimes arises when the proportion of one vapor to the other in the mixture changes or when the latent heat of one of the liquids is greater or smaller. For this purpose, there may be applied, as 25 indicated in Fig. 1, one or more valve members *w* operable from the exterior of the shell C and adapted to open or close ports in the baffle member G.

For brevity, the baffle structures, as F and 30 G, are referred to as vertically disposed, it being understood, however, that they need not extend accurately vertically, but may also be inclined, if suitable or desirable, so long as they have substantial extent in a vertical 35 direction:

What I claim is:

1. Apparatus for condensing a vapor mixture comprising a single shell, tube structure therein conducting cooling medium, vertically disposed baffle structure having a passage for condensate at its lower end and a passage for vapors intermediate its upper and lower ends, a vapor inlet on one side of said baffle structure, baffle structure disposed between said tube structure and said shell and over whose upper end flows the condensate flowing through said first named passage, and an outlet through which condensate flowing over said second baffle structure is discharged.

50 2. Apparatus for condensing a vapor mixture comprising a single shell, tube structure therein conducting cooling medium, vertically disposed baffle structure having a passage for condensate at its lower end and a passage for vapors intermediate its upper and lower ends, a vapor inlet on one side of said baffle structure, baffle structure over whose upper end flows the condensate flowing through said first named passage, an outlet through which is discharged said condensate flowing over said second baffle structure, and a vacuum pump connection to the vapor space on the side of said first named baffle structure opposite said vapor inlet.

65 3. Apparatus for condensing a vapor mix-

ture comprising a single shell, tube structure therein conducting cooling medium, vertically disposed baffle structure having a passage for condensate at its lower end and a passage for vapors intermediate its upper and lower ends, a vapor inlet on one side of said baffle structure, a second baffle structure on the opposite side of said first named baffle structure and forming a vertically extending chamber receiving at its upper end condensate flowing through said first named passage, and a condensate outlet communicating with said vertically extending baffle chamber.

4. Apparatus for condensing a vapor mixture comprising a single shell, tube structure therein conducting cooling medium, vertically disposed baffle structure having a passage for condensate at its lower end and a passage for vapors intermediate its upper and lower ends, a vapor inlet on one side of said baffle structure, a second baffle structure on the opposite side of said first named baffle structure and forming a vertically extending chamber receiving at its upper end condensate flowing through said first named passage, a condensate outlet communicating with said vertically extending baffle chamber, and a separate condensate outlet from the region in the bottom of said shell exterior to said vertically extending baffle chamber.

5. Apparatus for condensing a vapor mixture comprising a single vertically extending shell, vertical tube structure therein conducting cooling medium, vertically disposed baffle structure disposed between different portions of the tube structure and having a passage for condensate at its lower end and a passage for vapors intermediate its upper and lower ends, a vapor inlet on one side of said baffle structure adjacent the upper end of said shell, baffle structure over whose upper end flows the condensate flowing through said first named passage, and an outlet adjacent the bottom of said shell through which is discharged condensate flowing over said second baffle structure.

6. Apparatus for condensing a vapor mixture comprising a single vertically extending shell, vertical tube structure therein conducting cooling medium, vertically disposed baffle structure disposed between different portions of the tube structure and having a passage for condensate at its lower end and a passage for vapors intermediate its upper and lower ends, a vapor inlet on one side of said baffle structure adjacent the upper end of said shell, baffle structure over whose upper end flows the condensate flowing through said first named passage, an outlet adjacent the bottom of said shell through which is discharged condensate flowing over said second baffle structure, and an air pump connection adjacent the top of said shell on the side of said first named baffle structure opposite to said vapor inlet.

7. Apparatus for condensing a mixture of oil and water vapors comprising a single shell, tube structure therein conducting cooling medium, baffle structure extending vertically in said shell and having a passage adjacent its lower end for liquid oil and a second passage between its upper and lower ends for steam, an inlet for the vapor mixture on one side of said baffle structure, a baffle 5 chamber on the opposite side of said baffle structure through which flows liquid oil flowing through said first named passage, and an oil and water outlet communicating with said baffle chamber.

15 8. Apparatus for condensing a mixture of oil and water vapors comprising a single shell, tube structure therein conducting cooling medium, baffle structure extending vertically in said shell and having a passage adjacent its lower end for liquid oil and a second passage between its upper and lower ends for steam, an inlet for the vapor mixture on one side of said baffle structure, a baffle 20 chamber on the opposite side of said baffle structure through which flows liquid oil flowing through said first named passage, an oil and water outlet communicating with said baffle chamber, and means for separately drawing off water from the bottom of said shell 25 exterior to said baffle chamber.

30 9. Apparatus for condensing a mixture of oil and water vapors comprising a single shell, tube structure therein conducting cooling medium, baffle structure extending vertically in said shell and having a passage adjacent its lower end for liquid oil and a second passage between its upper and lower ends for steam, an inlet for the vapor mixture on one side of said baffle structure, a baffle 35 chamber on the opposite side of said baffle structure through which flows liquid oil flowing through said first named passage, an oil and water outlet communicating with said baffle chamber, and a passage for water to said oil 40 and water outlet from the bottom of said shell 45 exterior to said baffle chamber.

10. Apparatus for condensing a mixture of oil and water vapors comprising a single shell, tube structure therein conducting 50 cooling medium, baffle structure extending vertically in said shell and having a passage adjacent its lower end for liquid oil and a second passage between its upper and lower ends for steam, an inlet for the vapor mixture on 55 one side of said baffle structure, a baffle chamber on the opposite side of said baffle structure through which flows liquid oil flowing through said first named passage, an oil and water outlet communicating with said baffle 60 chamber, and a vacuum pump connection at the upper portion of said shell on the opposite side of said baffle structure from said vapor mixture inlet.

11. Apparatus for condensing a vapor mixture comprising a single shell, means for con- 65

ducting cooling medium successively through different regions in said shell, vertically disposed baffle structure defining said regions, a vapor inlet in communication with the region on one side of said baffle structure, a passage 70 in said baffle structure for flow of vapor to the region of lower temperature on the other side of said baffle structure, and a second passage for flow of condensate into heat transfer relation with said conducting means 75 disposed in said region of lower temperature.
